UNITED STATES PATENT OFFICE.

JOHN J. CHAPIN, OF DETROIT, MICHIGAN, ASSIGNOR TO BURROUGHS ADDING MACHINE COMPANY, OF DETROIT, MICHIGAN, A CORPORATION OF MICHIGAN.

TYPE-WRITING MACHINE.

1,167,977.

Specification of Letters Patent. Patented Jan. 11, 1916.

Application filed September 2, 1908. Serial No. 451,362.

To all whom it may concern:

Be it known that I, JOHN J. CHAPIN, a citizen of the United States, residing at Detroit, in the county of Wayne and State of Michigan, have invented certain new and useful Improvements in Type-Writing Machines, of which the following is a specification.

The present invention relates to mechanism in a typewriting machine for variously controlling the laterally shiftable paper carriage and one object is to provide an improved tabulator arrangement in which depression of a single key will cause the carriage to move to a columnar position predetermined by the setting of a stop, such key being automatically locked in operative position so that completion of the tabulating operation will not depend upon continued depression of the key by the operator and at the same time provision is made for preventing the tabulating devices taking effect until the key has been fully depressed. Furthermore, such key will be automatically released when the carriage has arrived at the proper position, repeated depression of the key being then permissible to cause a repetition of the tabulating operation.

A further object of the invention is to provide for effectively braking the carriage in its tabulating movements, provision being made in this connection for an increase in the braking effect as the carriage gains headway.

35 A still further object is to provide for rendering effective a keyboard lock by depression of the tabulator key so that no type can be struck while the tabulator key is in use.

40 The invention furthermore includes improvements in margin and end stop devices as well as tabulator stop devices, designed to facilitate manipulation for securing the various results in control of the paper carriage and the general use of the machine.

With these and incidental objects in view the invention consists in certain novel features of construction and combinations of parts, the essential elements whereof are 50 cited in the appended claims and a preferred form of embodiment of which is described in detail hereinafter and fully illustrated in

the accompanying drawings forming a part of this specification.

Of said drawings Figure 1 represents a 55 typewriting machine in top plan view containing the improvements of the present invention, some parts being omitted and others only partially illustrated for the sake of portraying more clearly those departments 60 of the machine with which the invention is more particularly concerned; Fig. 2 represents a fragmentary sectional view taken from front to rear with parts at normal; Fig. 3 is a similar view representing changed 65 relations of parts due to depression of the tabulator key; Fig. 4 is a fragmentary perspective of the tabulator bar and connected parts; Fig. 5 is a sectional detail of the tabulator stop devices; Fig. 6 is a fragmentary 70 isometric perspective of the tabulator bar and one of the tabulator stops; Fig. 7 is a detached perspective view of a member of one of the tabulator stops; Fig. 8 is a top plan view, broken away and condensed, of tabulator 75 mechanism; Fig. 9 is a fragmentary front elevation of braking devices; Fig. 10 is a section on the line 10—10 of Fig. 9; Fig. 11 is a section on the line 11—11 of Fig. 10; Fig. 12 is a fragmentary sectional front ele- 80 vation of end stop and key lock devices; Fig. 13 is a vertical section from front to rear of the same devices; Fig. 14 is a fragmentary sectionalized top plan view of the same; Fig. 15 is a view similar to Fig. 85 11 but with parts broken away to illustrate an alarm device; Fig. 16 is a section on the line 6—6 of Fig. 15; Fig. 17 represents the end stop device in perspective; Fig. 18 represents the same in horizontal section; Fig. 19 90 is a similar horizontal section of a modified construction; Fig. 20 is a front elevation of the margin stop; Fig. 21 is a cross-section of the same; and Fig. 22 a bottom view thereof with the body portion broken away.

95 In the drawings the reference numeral 2 generally designates the supporting framework of the machine; 3 the character key levers which will be appropriately connected with type bars which in the present instance 100 operate on the so-called front strike principle; the centering guide being designated by the numeral 4, a ribbon vibrator by the numeral 5 and the ribbon spools by the

numeral 6. The location of the platen 7 is indicated by a dotted line in Fig. 1 but appears in cross-section in Fig. 2 and the reference numeral 8 designates the frame of the paper carriage. In the latter an escapement rack 9 is hung by pivoted side arms 10 and said rack engages a pinion 11 (Fig. 1) of an escapement mechanism to be operated by the character key levers and a spacing bar 12 in any suitable or well-known manner. For tabulating purposes the rack 9 will be lifted out of engagement with the escapement pinion 11. This is effected through the medium of a radial arm 13 secured to a rock shaft 14 journaled in bearings at the back of the supporting framework, said arm 13 having a journal stud 15 screwed in its end (Fig. 10), a sleeve 16 loose on said stud and a roller 17 loose on the sleeve. A flange 18 of the escapement rack overlies said roller and it will be obvious that turning of the rock shaft to lift the arm 13 will have the effect of raising the rack out of engagement with the escapement pinion.

25 The rock shaft 14 has secured to it near the right hand end an angular arm 19, a depending part of which terminates in a laterally bent portion 20 through which loosely passes a screw 21 (Fig. 2), said screw carrying a thumb nut 22 on the lower side of said laterally turned portion of the arm and notched to engage a projection on the latter for locking purposes. Said screw at its upper end holds one extremity of a spiral spring 23, the opposite end of which is attached to an arm 24 loose on the rock shaft 14 and notched for engagement of a stud 19^a on the arm 19. The forward end of said arm 24 is coupled to a depending link 25 which at its lower end is pivotally connected with a lever 26 pivoted intermediate its ends at 27 to a tabulator key lever 28. The latter is pivotally mounted intermediate its ends as at 29 on the framework of the machine and 45 at its forward end carries a tabulator key 30 (Fig. 1). A spring 31 connects the forward end of the lever 26 with a stud on the framework and said lever 26 in rear of its pivot underlies a stud 32 on the lever 28 so 50 that the spring 31 normally operates to depress the rear portion of the tabulator key lever and elevate its front portion. A latch 33 pivoted at 34 to the framework and drawn rearwardly by a spring 35 normally restrains the lever 26 by engaging over a stud 36 projecting laterally from said lever in rear of its pivot (Fig. 2). Consequently when the tabulator key is first depressed the rear end of the lever 26 will not move up 55 with the rear portion of the tabulator key lever but said lever 26 will assume the position indicated in dotted lines in Fig. 3. The latch 33 is formed on its rear side at a point below the shoulder which engages the stud 36, with a cam rise or projection 37 and the

lever 28 at its rear end has a depending portion 38 with a laterally projecting stud 39 at the lower extremity, adapted as the tabulator key lever completes its movement under depression of the tabulator key to act upon said cam rise and displace the latch, releasing the lever 26. Thereupon the spring 31 whose tension has been considerably increased by reason of the detention of the lever 26, will rock said lever to the position 75 shown in full lines in Fig. 3, lifting the arm 24 through the medium of the link 25, and said arm 24 through the medium of the spring 23 lifts the arm 19, rocking the shaft 14 and raising the arm 13 which lifts the 80 escapement rack out of engagement with the escapement pinion.

On the rear bar of the carriage frame there is secured a lug 40 beveled on the right hand side and squared off on the left hand side, the latter adapted to coöperate with the adjustable stop devices presently to be described, for properly locating the carriage at the desired columnar position when the escapement rack is released as above described. 90 A tabulator bar 41 square in cross section is mounted to rock in bearings in the main framework, also being longitudinally movable to a limited extent in its bearings. Said bar is marked with a scale on its top side 95 and a similar scale on its front side and is channeled longitudinally in its rear side as illustrated in Fig. 4 and notched from end to end above and below the channel as shown at 42. On this tabulator bar there are permanently arranged any desired number of slidingly adjustable stop devices. As they are duplicates of each other a description of one will suffice for all. The stop device comprises a body portion 43 channeled 100 to embrace the under and front and rear sides of the bar and having a cap plate 44 extending over the top of said bar. This cap plate is open in the center as at 45 to expose marks on the top scale of the bar and is marked for registry with said scale. The front of the body portion 43 is also open as shown at 46 to expose the scale on the front side of the bar and the front edge of the body portion which comes flush with the front side of the bar is marked for registry with said scale, see Fig. 6. There projects from the body portion 43 above the opening 46 a square lug 47 for the lug 40 on the carriage to abut. The body portion 43 in rear of the bar is bored to accommodate a sliding dog 48 having a stem 49 sliding through an opening in the cap plate 44. Said dog is formed on a flattened front surface with spaced pairs of teeth 50 (Fig. 7) to engage the notches of the bar 41. An inverted cup-shaped knob 49^a is screwed to the end of the stem 49 and a spiral spring 48^a surrounds the latter within said knob normally elevating the dog to engage its teeth 50 with the 110

115

120

125

130

notches of the tabulator bar as shown in Fig. 5. Pressure on the knob 49^a will disengage said teeth from said notches so that the upper set of teeth will be moved into the channel of the tabulator bar and the lower set of teeth will be carried below said channel when the stop piece can be slid along the tabulator bar and located at any point desired.

10 The tabulator bar normally maintains an angular position in which the lug 47 of the stop piece is above the plane of movement of the lug 40 on the carriage so that the latter lug will freely pass in ordinary writing operations of the machine. Depression of the tabulator key not only results in disengaging the escapement rack from the escapement pinion as already described but also has the effect of rocking the tabulator bar to bring the stop lug in the path of the carriage lug. For this purpose there is secured to the left hand end of the tabulator bar a plate 51 bifurcated in its lower edge to receive the stud 52 of an arm 53 secured to the rock shaft 14, said arm being connected by a comparatively light spring 54 with said plate 51, all as shown in Figs. 2 and 3. In the normal position of the rock shaft 14 the stud 52 is against the front side of the bifurcation in the plate 51 holding the tabulator bar tilted as shown in Fig. 2. When the rock shaft is moved by depression of the tabulator key as above described, the arm 53 swings rearward and through the medium 35 of the spring 54 rocks the tabulator bar so as to bring the stop lug in the line of the carriage lug.

A spiral spring 60 seated in a recess of the framework surrounding the left hand 40 journal of the tabulator bar bears against the plate 51, tending to thrust said bar to the right, but is normally restrained from so doing by a lever 61 pivoted intermediate its ends to a lug of the framework as at 45 63, bifurcated at its upper end to engage a circumferential groove 64 in the tabulator bar (Fig. 4) and normally engaged at its lower end with the right hand side of an angular rearward extension 24' of the before-mentioned arm 24 which is fast on the rock shaft 14. It is obvious that the spring 60 tends to rock the lower end of said lever 61 to the left which normally is prevented by said extension 24' but upon the completion 50 of depression of the tabulator key and consequent rocking of the shaft 14 said extension is moved down beyond the end of the lever 61 whereupon the spring 60 acts and said lever moves over the extension locking 55 the train of mechanism which extends to the tabulator key and thus holding the same depressed. When, however, the carriage lug strikes the stop lug the spring 60 is overcome and the tabulator bar moved to the 60 left carrying the lower end of the lever 61

back to the right and releasing the lever 24 whereupon it returns to normal together with other parts operated by the tabulator key, the latter of course rising.

In order to provide for release of the tabulator key in an extreme position of the carriage to the left a permanent stop piece 65 is secured on the left hand end of the tabulator bar having a lug wide enough to continue engagement with the carriage lug 75 when the bar has returned to normal position, thereby preventing the tabulator key remaining depressed should it be depressed with the carriage at this extreme position. It will of course be obvious that upon release of the rock shaft 14 and its return to normal the arm 53 will tilt the tabulator bar.

If the tabulator key should inadvertently be held down by finger pressure while the carriage is pushed back to the left, no damage can result for the inclined side of the lug 40 will act with a camming effect upon the lugs 47, and the spring 54 will yield to permit the consequent rocking of the tabulator bar.

It will be observed that the provision of scales on both the top and front of the tabulator bar and formation of the stop devices to make either scale available, conduces to great convenience in the use of the tabulating mechanism.

Besides performing the function of lifting the escapement rack the arm 13 also performs the function of applying a brake to retard the movement of the carriage in a tabulating operation. The before-mentioned sleeve 16 is formed with a pinion 67 which when the arm 13 is thrown upward comes into mesh with the escapement rack so that when the carriage moves to the left in a tabulating operation the sleeve 16 will be rotated. This sleeve has secured to its inner end a ratchet wheel 68 (Fig. 11) and a surrounding collar 69 carries a pawl 70 held by a spring 70^a in engagement with said ratchet so that said collar will be rotated with the sleeve when the carriage is moving to the left. A coiled spring 71 surrounds the collar, being secured thereto at its inner end. The outer end of said spring is attached to a drum 72 which surrounds it and is loosely journaled upon the sleeve 16. On a suitable bracket of the framework there is secured a brake shoe 73 which extends above said drum and is adapted to be contacted thereby when the arm 13 is raised. The first effect produced in this braking construction by an operation of the tabulator mechanism is to wind up the spring 71. This alone would suffice to retard the movement of the carriage when that movement is not of any considerable extent, but of course there is a limit to the winding of the spring or the ability of the

carriage to overcome the same and when this limit is reached the drum 16 will be rotated as the carriage continues on its way. The carriage is then further retarded by the friction between the drum and the brake shoe 73.

The before-mentioned spring connection between the fast and loose arms 19 and 24 on shaft 14 provides for the friction drum 10 being yieldingly pressed against the brake, — the spring 31 also having a similar effect, — so that a maintained braking pressure is insured without relying at all upon continued finger pressure on the tabulator key.

15 It is desirable to lock the character key levers against operation while the tabulator key is in action and to this end the following mechanism is provided: A rock shaft 74 is arranged between the lower parts of 20 the framework (Figs. 12, 13 and 14) and where it extends under the tabulator key lever 28 it is equipped with an arm 75 having a roller stud 76 against which said lever operates when the tabulator key is depressed. Near the opposite end of said rock shaft there is secured an arm 77 having at 25 its upper extremity a cam finger 78. The latter engages the front edge of a vertically extending lever 79 pivoted at 80 in a swivel piece 81 journaled in the supporting framework. Rocking of the shaft 74 causes the cam finger 78 to act against said lever 79 and swing its lower part to the right. The lower end of this lever is jointed at 82 to 30 a horizontally disposed lever 83 arranged to swing from side to side, said lever being pivoted at its rear end to the framework as shown at 84 (Fig. 13). At an intermediate point said lever engages a pin 85 on a 35 sliding shaft 86 extending across beneath the character key levers. This shaft carries a series of collars 87 normally out of line with arms 88 of a bail whose cross rod 89 extends under said key levers, said bail 40 being in the present instance the escapement bail. When the tabulator key is depressed and the lever 83 swung to the right, said shaft 86 is shifted to carry its collars 87 under the arms of said bail, thus blocking 45 downward movement of the character key levers and of course preventing the striking of any type. This same effect is produced when the end of a line is reached in ordinary writing as will presently be described.

50 55 The upper end of the lever 79 is coupled to an arm 90 of a plate 91 secured to and underlying a sleeve 92 which is arranged to slide to a limited extent on the front way-rod 93 on which the carriage 8 travels, said sleeve being normally held to the right by a spring 94 in a chamber of the framework surrounding the left hand end of said rod 93 (Fig. 12). On said sleeve there is adjustably mounted an end stop piece comprising a body portion 95 partially embrac-

ing the sleeve, the latter being open along the greater portion of its upper side so that the carriage roller 96 can traverse the rod 93 the full extent. The body portion 95 (Fig. 18) is recessed to receive a pawl or dog 97 pivoted therein and engaging a longitudinally-notched portion 98 of the sleeve 92, a spring 99 serving to enforce such engagement. Said pawl or dog is formed with a knob or handle 100, and a finger piece 101 is formed on the body portion 95 so that the end stop can be conveniently manipulated by placing the forefinger on this piece 101 and the thumb on the knob 100. The spring 99 has formed integrally with it an index 100 pointer 102 for traversing a scale 103 on the framework. The end stop piece has a lug 104 (Fig. 16) occupying a spline groove 105 in the sleeve 92 so that said end stop while adjustable longitudinally of the sleeve 105 does not turn relatively thereto. However, the sleeve itself is capable of a limited rotary movement on the rod 93 for the purpose of sounding an alarm to indicate the approach to the end of a line of writing. The 100 plate 91 has a downwardly-extending arm 106 carrying at its lower end a bell clapper 107 (Fig. 15) and there is mounted in a suitable location on the frame of the machine a bell 108 to be struck by said clapper. A 105 spring 110 connects the arm 106 with a stud on the framework holding the said arm rearwardly and the sleeve 92 rocked rearward. The connection between the upper end of the lever 79 and the arm 90 is such as to permit the rocking of the plate 91 without affecting said lever. On the front bar of the carriage 8 there is pivoted a gravity stop piece 111 (Fig. 12) and on the rear side of the body portion 95 of the end stop piece there is formed a beveled lug 112 which said gravity stop piece rides over, rocking the end stop and the sleeve 92 with the effect of throwing forward and then releasing the bell clapper to sound the alarm. The body 110 of the end stop is further formed on its rear side with a lug 113 spaced from the lug 112 and said gravity stop piece 111 is adapted to encounter said lug 113 and thereby shift the end stop and sleeve 92 to the left against the stress of the spring 94, thus rocking the lever 79 and locking the character key levers in the same way that they are locked by depression of the tabulator key as before described. A modified form of end stop is shown in Fig. 19 where only a single manipulating handle is required. The numeral 95' designates the body portion of the end stop which is recessed on the forward side of the sleeve 92 for the reception of a pivoted dog 97' having a tail 97'', said tail having a cam surface engaged by a complementary edge of a pivoted handle piece 101'. A flat spring 99' secured to the body portion 95' bears against the back of the dog 130

97'. It will be seen that side pressure on the finger piece 101' will disengage the dog from the ratcheted portion 98 of the sleeve and that the end stop can be re-adjusted by 5 the same finger piece or handle.

A margin stop is provided of a construction somewhat similar to that of the end stop (Figs. 20-22). It comprises a body portion 114 partially surrounding the way- 10 rod 93 which is ratcheted for a distance shown at 115 to cooperate with a dog 116 pivotally mounted in the body portion 114 and having a knob 117 by which to manipulate it. The body portion is formed with 15 a finger piece 118 projecting from the end opposite that where the knob of the dog projects and this margin stop can thus be manipulated conveniently and effectively as described with reference to the end stop. 20 Engagement of the dog with the ratchet is enforced by a flat spring 119 secured to the body portion 114 on the underside thereof and having formed integral with it an index finger 120 overlying the scale 103. This 25 spring has also formed integrally with it a portion 121 extending rearwardly into an opening in the underside of the body portion 114 and thence laterally in a slot of such body portion, this laterally extending 30 portion standing on edge and occupying a longitudinal groove 122 in the underside of the way-rod. The spring thus serves to hold the margin stop yieldingly in a normal position with its front portion lowered. A 35 stop lug 123 on the upper rear portion of the margin body piece 114 is adapted to be struck by a contact plate 124 on the carriage frame to limit the movement of the carriage to the right. The margin stop can, however, 40 be tilted against the pressure of the spring so as to permit the carriage to be moved farther to the right if occasion should require. The stop lug is beveled on the upper side so that the carriage can move 45 back to the left riding over the said lug against the spring pressure. In this connection it might be stated that the capability of rocking of the end stop piece with the sleeve on which it is mounted, can be utilized 50 in cases where it may be desired to write beyond the line limit set. The pivotal mounting of the stop piece 111 on the carriage provides for its riding over the lug 113 when the carriage moves back to the right. 55 It will now be seen that the above-described constructions are well calculated to fulfil the various objects primarily stated, but at the same time it is to be understood that the invention is not necessarily limited to 60 those constructions but may be carried out differently.

What I claim is:

1. In a typewriting machine, the combination of a laterally shiftable spring-drawn 65 paper carriage; an escapement rack mov-

ably mounted thereon, one or more movable tabulator stops, normally restrained spring-actuated means for displacing the rack and moving a tabulator stop to effective position, and a tabulator key controlling said means and adapted to release the same toward the end of its operation. 70

2. In a typewriting machine, the combination of a laterally shiftable spring-drawn paper carriage; an escapement rack mov- 75 ably mounted thereon, one or more movable tabulator stops, normally restrained spring-actuated means for displacing the rack and moving a tabulator stop to effective position, and a tabulator key adapted in the first part of its movement to put the spring of said means under tension and in the latter part of its movement to release said means. 80

3. In a typewriting machine, the combination of a laterally shiftable spring-drawn paper carriage; an escapement rack pivot- 85 ally mounted thereon, one or more movable tabulator stops, normally restrained spring-actuated means for displacing the rack and moving a tabulator stop to effective position, and a tabulator key controlling said means and adapted to release the same toward the end of its operation. 90

4. In a typewriting machine, the combination of a laterally movable spring-drawn paper carriage; a tabulator key lever; a second lever controlled thereby but movable independently thereof; a spring for effecting such latter movement adapted to be put under tension by the key lever; a latch for restraining the second lever adapted to be tripped by the key lever; and carriage release and stop setting means operated by the second lever. 95 100

5. In a typewriting machine, the combination of a laterally movable spring-drawn paper carriage; a tabulator key lever; a secondary lever mounted intermediate its ends on the key lever; a spring applied to one end of said secondary lever; a latch en- 105 gaging the other end of said secondary lever and adapted to be tripped by the key lever; and carriage release and stop setting means operated by the secondary lever. 110

6. In a typewriting machine, the combination of a laterally movable spring-drawn paper carriage; a tabulator key lever; a secondary lever mounted intermediate its ends on the key lever; a spring applied to one end of said secondary lever; a latch en- 115 gaging the other end of said secondary lever and having a cam edge; a pin or stud on the key lever adapted to engage said cam edge to trip the latch; and carriage release and stop setting means operated by the second- 120 ary lever. 125

7. In a typewriting machine, the combination of a laterally movable spring-drawn paper carriage; a tabulator key lever; a sec- 130 ondary lever mounted intermediate its ends

- on the key lever, the latter having a lateral projection extending over the secondary lever on one side of the latter's pivot; a spring applied to said secondary lever on the other side of its pivot; a latch engaging the secondary lever and adapted to be tripped by the key lever; and carriage release and stop setting means operated by the secondary lever.
8. In a typewriting machine, the combination of a laterally movable spring-drawn paper carriage; a tabulator key lever; a second lever controlled thereby but movable independently thereof; a spring for effecting such latter movement adapted to be put under tension by the key lever; a latch for restraining the second lever adapted to be tripped by the key lever; a rock shaft cranked and linked to the second lever; and carriage release and stop setting means operated by said rock shaft.
9. In a typewriting machine, the combination of a laterally movable spring-drawn paper carriage; a tabulator key lever; a second lever controlled thereby but movable independently thereof; a spring for effecting such latter movement adapted to be put under tension by the key lever; a latch for restraining the second lever adapted to be tripped by the key lever; a rock shaft; a crank arm loose thereon; a link connecting said crank arm with the said second lever; a crank arm fast on said shaft; a spring connecting the two crank arms; and carriage release and stop setting means operated by the rock shaft.
10. In a typewriting machine, the combination of a laterally shiftable spring-drawn paper carriage; a rock shaft; carriage releasing and braking means operated thereby; a crank arm fast on said shaft; a crank arm loose on said shaft; a spring connecting the two crank arms; and a tabulator key and connections for operating the loose crank arm.
11. In a typewriting machine, the combination of a laterally movable spring-drawn paper carriage; a tabulator key lever; a second lever controlled thereby but movable independently thereof; a spring for effecting such latter movement adapted to be put under tension by the key lever; a latch for restraining the second lever adapted to be tripped by the key lever; a rock shaft; a crank arm loose thereon; a link connecting said crank arm with the said second lever; a crank arm fast on said shaft; a spring connecting the two crank arms; and carriage releasing and braking means operated by said rock shaft.
12. In a typewriting machine, the combination of a laterally movable spring-drawn paper carriage; a tabulator key lever; a secondary lever mounted intermediate its ends on the key lever; a spring applied to one end of said secondary lever; a latch engaging the other end of said secondary lever and adapted to be tripped by the key lever; a rock shaft; a crank arm loose thereon; a link connecting said crank arm with said secondary lever; a crank arm fast on the rock shaft; and carriage releasing and braking means operated by said rock shaft.
13. In a typewriting machine, the combination of a stationary frame, a laterally movable spring-drawn paper carriage having a tabulator projection; a rocking and longitudinally movable spring-held tabulator bar journaled in the stationary frame at its ends, one or more stops adjustable on said bar, means for rocking the tabulator bar to present its stop in the path of the carriage projection, and means for locking the bar in rocked position, with provisions for unlocking the same automatically as a result of the tabulator projection and of the carriage encountering the stop on the bar and moving it longitudinally, the result of rocking of the latter taking the stop out of the path of the projection.
14. In a typewriting machine, the combination of a laterally movable spring-drawn paper carriage having a tabulator projection, a rocking and longitudinally movable spring-held tabulator bar journaled in the stationary frame at its ends; one or more stops adjustable on said bar; means for rocking the tabulator bar to present its stop in the path of the carriage projection; means for locking the bar in rocked position, with provisions for unlocking the same automatically as a result of the tabulator projection of the carriage encountering the stop on the bar and moving it longitudinally, the result of rocking action of the latter taking the stop out of the path of the projection, and a permanent stop on the bar of dimensions to always stand in the path of the projection.
15. In a typewriting machine, the combination of a laterally movable spring-drawn paper carriage having a tabulator projection; a rocking and longitudinally movable spring-held tabulator bar; one or more stops adjustable on said bar; a rock shaft journaled independently of and operatively connected with said bar; means for rocking said shaft and thereby the bar to present a stop of the latter in the path of the carriage projection; and means for locking said rock shaft adapted to be released by the endwise movement of the bar resultant from contact of the carriage projection with the stop.
16. In a typewriting machine, the combination of a laterally movable spring-drawn paper carriage having a tabulator projection; a rocking and longitudinally movable spring-held tabulator bar; one or more stops adjustable on said bar; a rock shaft operatively connected with said bar; means for

rocking said shaft and thereby the bar to present a stop of the latter in the path of the carriage projection; a lock arm on said shaft; and a locking lever engaged with the 5 bar and adapted to engage the lock arm upon the rocking of the shaft.

17. In a typewriting machine, the combination of a laterally movable spring-drawn paper carriage having a tabulator projection;

10 a rocking and longitudinally movable spring-held tabulator bar; one or more stops adjustable on said bar; a tabulator key lever; a second lever controlled thereby but movable independently thereof; a spring 15 for effecting such latter movement adapted to be put under tension by the key lever; a latch for restraining the second lever adapted to be tripped by the key lever; means operated by said second lever for rocking 20 the tabulator bar to present its stop to the carriage projection; and means for locking the bar in rocked position, with provisions for unlocking the same automatically as a result of the tabulator projection of the carriage encountering the stop on the bar, the resultant rocking of the latter taking the stop out of the path of the projection.

18. In a typewriting machine, the combination of a laterally movable spring-drawn 30 paper carriage having a tabulator projection; a rocking and longitudinally movable spring-held tabulator bar; one or more stops adjustable on said bar; a rock shaft operatively connected with said bar; a tabulator 35 key lever; a second lever controlled thereby but movable independently thereof; a spring for effecting such latter movement adapted to be put under tension by the key lever; a latch for restraining the second 40 lever adapted to be tripped by the key lever; means operated by said second lever for rocking said shaft and thereby the bar to present a stop of the latter in the path of the carriage projection; and means for locking 45 said rock shaft adapted to be released by the endwise movement of the bar resultant from contact of the carriage projection with the stop.

19. In a typewriting machine, the combination of a laterally movable spring-drawn 50 paper carriage having a tabulator projection; a rocking and longitudinally movable spring-held tabulator bar; one or more stops adjustable on said bar; a rock shaft 55 operatively connected with said bar; a crank arm loose on said shaft and having a projecting locking arm, a locking lever engaged with the bar and adapted to engage the locking arm upon the rocking of the shaft, a 60 crank arm fast on the shaft, a spring connecting the two crank arms, and means for operating the first-mentioned crank arm.

20. In a typewriting machine, the combination of a tabulating rail having a scale

along one side and a double series of teeth 65 along another with a channel between; and a stop mounted to slide on said bar and having an open-center portion extending over the scale and marked for registry therewith and a spring-held slide dog having spaced 70 teeth, one to engage one series of teeth on the bar and the other to engage the other series of teeth on said bar.

21. In a typewriting machine, the combination of a laterally shiftable spring-drawn 75 paper carriage having an escapement rack movably mounted upon it, means for displacing the rack and setting a stop to limit the resultant movement of the carriage, a gear movable into and out of engagement 80 with the rack and a brake thrown into operative connection with the gear by the movement of the latter into engagement with the rack.

22. In a typewriting machine, the combination of a laterally shiftable spring-drawn 85 paper carriage having an escapement rack, escapement means coöperating with the rack, means for releasing the engagement of the escapement means with the rack, a gear 90 movable into and out of engagement with the rack and braking means for the gear thrown into operative relation thereto by the movement of the gear into engagement with the rack. 95

23. In a typewriting machine, the combination of a laterally shiftable spring-drawn paper carriage having an escapement rack movably mounted upon it; means for displacing the rack and setting a stop to limit 100 the resultant movement of the carriage, and braking means comprising a gear movable into and out of engagement with the rack, a drum turned by said gear, and a stationary shoe with which the drum is brought 105 into engagement when the gear is brought into engagement with the rack.

24. In a typewriting machine, the combination of a laterally shiftable spring-drawn 110 paper carriage having an escapement rack movably mounted upon it; means for displacing the rack and setting a stop to limit the resultant movement of the carriage; and braking means comprising a gear movable 115 into and out of engagement with the rack; a spring attached at one end to said gear, a drum to which the other end of the spring is attached and braking means for the drum.

25. In a typewriting machine, the combination of a laterally shiftable spring-drawn 120 paper carriage having an escapement rack movably mounted upon it; means for displacing the rack and setting a stop to limit the resultant movement of the carriage; and braking means comprising a gear movable 125 into and out of engagement with the rack; a spring arranged to be put under tension by said gear; a drum connected with said

spring; and a shoe engaged by the drum when the gear is in engagement with the rack.

26. In a typewriting machine, the combination of a laterally shiftable spring-drawn paper carriage having an escapement rack movably mounted upon it; means for displacing the rack and setting a stop to limit the resultant movement of the carriage; and 10 braking means comprising a gear movable into and out of engagement with the rack; a drum having a one-way connection with said gear, and a shoe engaged by said drum when the gear is in engagement with the 15 rack.

27. In a typewriting machine, the combination of a laterally shiftable spring-drawn paper carriage having an escapement rack movably mounted upon it; a movable arm 20 supporting an idler adapted to engage and displace the rack, a gear carried by said arm and adapted to engage the rack when thus displaced, a spring attached at one end to said gear, a drum to which the other end 25 of the spring is attached and braking means for the drum.

28. In a typewriting machine, the combination of a laterally shiftable spring-drawn paper carriage having an escapement rack 30 movably mounted upon it; a movable arm supporting an idler adapted to engage and displace the rack, a gear carried by said arm and adapted to engage the rack when thus displaced, a drum arranged to be turned by 35 the gear, and a shoe for said drum to engage.

29. In a typewriting machine, the combination of a laterally shiftable spring-drawn paper carriage having an escapement rack movably mounted upon it; a movable arm 40 supporting an idler adapted to engage and displace the rack, a gear carried by said arm and adapted to engage the rack when thus displaced, a spring arranged to be put under tension by said gear, a drum connected with 45 said spring; and a shoe for said drum to engage.

30. In a typewriting machine, the combination of a laterally shiftable spring-drawn paper carriage having an escapement rack 50 movably mounted upon it; a rock shaft having a radial arm with a journal bearing, a gear on the latter adapted to engage the rack, a spring arranged to be put under tension by the gear, a drum to which the other 55 end of the spring is attached, a braking shoe into contact with which the drum is brought by the rocking of the shaft, and means for turning the rock shaft and setting a stop to limit the movement of the carriage.

60 31. In a typewriting machine, the combination of a laterally shiftable spring-drawn paper carriage having an escapement rack 65 movably mounted upon it; a rock shaft having a radial arm with a journal bearing; a gear and idler on the latter, the idler adapt-

ed to displace the rack while the gear engages the same, a spring arranged to be put under tension by the gear, and means for turning the rock shaft and setting a stop to limit the movement of the carriage. 70

32. In a typewriting machine, the combination of a laterally shiftable spring-drawn paper carriage having an escapement rack movably mounted upon it; a rock shaft having a radial arm with a journal bearing; a gear on the latter adapted to engage the rack; a drum turned by said gear, a stationary shoe arranged to be engaged by the drum when the gear engages the rack and means for turning the rock shaft and setting a stop 80 to limit the movement of the carriage. 75

33. In a typewriting machine, the combination of a laterally shiftable spring-drawn paper carriage having an escapement rack movably mounted upon it; a rock shaft having a radial arm with a journal bearing; a gear and idler on the latter, the idler adapted to displace the rack while the gear engages the same; a drum turned by said gear, a shoe engaged by the drum, and 90 means for turning the rock shaft and setting a stop to limit the movement of the carriage. 85

34. In a typewriting machine, the combination of a laterally shiftable spring-drawn paper carriage having an escapement rack 95 movably mounted upon it; a rock shaft having a radial arm with a journal bearing; a gear on the latter adapted to engage the rack, a spring arranged to be put under tension by the gear; a drum connected with 100 said spring, a shoe for said drum to engage, and means for turning the rock shaft and setting a stop to limit the movement of the carriage.

35. In a typewriting machine, the combination of a laterally shiftable spring-drawn paper carriage having an escapement rack movably mounted upon it; a rock shaft having a radial arm with a journal bearing; a gear and idler on the latter, the idler 110 adapted to displace the rack while the gear engages the same, a spring arranged to be put under tension by the gear; a drum connected with said spring, a shoe for said drum to engage, and means for turning the 115 rock shaft and setting a stop to limit the movement of the carriage.

36. In a typewriting machine, the combination of a laterally shiftable spring-drawn paper carriage having an escapement rack 120 movably mounted upon it and means for controlling the speed of movement of the carriage when the rack is displaced, said means comprising a supporting shaft, a sleeve loose thereon and having a gear for 125 engaging the rack and a ratchet, a collar loose on the sleeve and having a pawl engaging said ratchet, a coiled spring surrounding said collar and secured at one end thereto, a drum loosely mounted on the 130

- sleeve and inclosing said spring, one end of the latter being secured thereto, and a shoe engaged by said drum when the gear is in engagement with the rack.
5. 37. In a typewriting machine, the combination of a laterally shiftable spring-drawn paper carriage having an escapement rack movably mounted upon it; and means for displacing the rack and controlling the speed of movement thereof, said means comprising a supporting shaft, a sleeve loose thereon and having a gear for engaging the rack and a ratchet, an idler loose on the sleeve and adapted to displace the rack, a collar loose on the sleeve and having a pawl engaging said ratchet, a coiled spring surrounding said collar and secured at one end thereto, a drum loosely mounted on the sleeve and inclosing said spring, one end of the latter being secured thereto, and a shoe engaged by said drum when the gear is in engagement with the rack.
10. 38. In a typewriting machine, the combination of a laterally shiftable spring-drawn paper carriage having an escapement rack movably mounted upon it and means for controlling the speed of movement of the carriage when the rack is displaced, said means comprising a rock shaft having a radial arm with a journal bearing, a sleeve loose on the latter and having a gear for engaging the rack and a ratchet, a collar loose on the sleeve and having a pawl engaging said ratchet, a coiled spring surrounding said collar and secured at one end thereto, a drum loosely mounted on the sleeve and inclosing said spring, one end of the latter being secured thereto, and a shoe engaged by said drum when the gear is in engagement with the rack.
15. 39. In a typewriting machine, the combination of a laterally shiftable spring-drawn paper carriage having an escapement rack movably mounted upon it; and means for displacing the rack and controlling the speed of movement thereof, said means comprising a rock shaft having a radial arm with a journal bearing, a sleeve loose on the latter and having a gear for engaging the rack and a ratchet, a collar loose on the sleeve and having a pawl engaging said ratchet, a coiled spring surrounding said collar and secured at one end thereto, a drum loosely mounted on the sleeve and inclosing said spring, one end of the latter being secured thereto, and a shoe engaged by said drum when the gear is in engagement with the rack.
20. 40. In a typewriting machine, the combination of a laterally shiftable spring-drawn paper carriage; escapement mechanism comprising a universal bail; key levers for operating the same; type bars operated by the key levers; a slide rod with one or more enlargements to block said universal bail; tab-
- ulating means comprising carriage release and stop setting devices and a key lever; and means operated by said key lever for shifting the slide rod.
41. In a typewriting machine, the combination of a carriage having a support a stationary carriage rail or rod with which the support directly engages; a sleeve slidable thereon; an end-stop on the sleeve adjustable lengthwise thereof; a paper carriage having an abutment to act against said stop and move it and the sleeve lengthwise the rail or rod; keys; and means for locking the same operatively connected with the said sleeve.
42. In a typewriting machine, the combination of a carriage having a support a stationary carriage rail or rod with which the support directly engages; a sleeve slidable and rotatable thereon; a stop longitudinally adjustable on said sleeve and rotatively engaged therewith; a paper carriage having an abutment to act against said stop and move it and the sleeve lengthwise the rail or rod; keys; and means for locking the same operatively connected with the said sleeve.
43. In a typewriting machine, the combination of a laterally movable paper carriage having an abutment; an end-stop for said abutment to encounter, adapted to move in the same direction as the carriage; key levers; a universal bail; a slide rod with one or more abutments to intercept said bail; and connections between said rod and the end-stop for giving an endwise movement to the slide rod.
44. In a typewriting machine, the combination of a laterally movable paper carriage having an abutment; an end-stop for said abutment to encounter, adapted to move in the same direction as the carriage; key levers; a universal bail; a slide rod with one or more abutments to intercept said bail; a lever applied to said rod and adapted to give the same an endwise movement; and a second lever connected with the first and with the said end-stop.
45. In a typewriting machine, the combination of a carriage, a support therefor, a carriage rail or rod with which said support directly engages; a sleeve slidable thereon; an end-stop on the sleeve adjustable lengthwise thereof; a paper carriage having an abutment to act against said stop and move it and the sleeve lengthwise the rail or rod; keys; and means for locking the same operatively connected with the said sleeve, said means comprising a slide rod with one or more abutments to intercept the keys, and a lever for giving the slide rod endwise movement.
46. In a typewriting machine, the combination of a carriage rail or rod; a sleeve slidable thereon; an end-stop on the sleeve adjustable lengthwise thereof; a paper car-

riage having an abutment to act against said stop and move it and the sleeve lengthwise the rail or rod; key levers; a universal bail; a slide rod with one or more abutments to intercept said bail; a lever applied to said rod; and a second lever connected with the first and with the said sleeve.

47. In a typewriting machine, the combination of a carriage rail or rod; a sleeve 10 slidable thereon; an end-stop on the sleeve adjustable lengthwise thereof; a paper carriage having an abutment to act against said stop and move it and the sleeve lengthwise the rail or rod; keys; means for locking the same operatively connected with the said sleeve; and a spring normally holding the sleeve out of position for locking the keys.

48. In a typewriting machine, the combination of a carriage rail or rod; a sleeve 20 slidable and rotatable thereon; a stop longitudinally adjustable on said sleeve and rotatively engaged therewith and having a cam and a stop projection; a paper carriage having an abutment to ride over the cam and act 25 against the stop projection; an arm on the sleeve having a branch carrying a bell striker; a bell; keys; and means for locking the latter operated by the sleeve in its longitudinal movement.

49. In a typewriting machine, the combination of a carriage rail or rod; a sleeve 30 slidable and rotatable thereon; a stop longitudinally adjustable on said sleeve and rotatively engaged therewith and having a cam and a stop projection; a paper carriage having an abutment to ride over the cam and act 35 against the stop projection; an arm on the sleeve having a branch carrying a bell striker; a bell; key levers; a slide rod adapted to block movement of the key levers; and lever connections between said slide rod and the arm of the sleeve.

50. In a typewriting machine, the combination of a laterally movable paper carriage 45 having an abutment; an end-stop for said abutment to encounter, adapted to move in the same direction as the carriage; keys; means for locking the same by such movement of said stop; and a tabulator key 50 adapted to operate said locking means.

51. In a typewriting machine, the combination of a carriage rail or rod; a sleeve 55 slidable thereon; an end-stop on the sleeve adjustable lengthwise thereof; a paper carriage having an abutment to act against said stop and move it and the sleeve lengthwise the rail or rod; keys; means for locking the same operatively connected with the said sleeve; and a tabulator key adapted to operate 60 said locking means.

52. In a typewriting machine, the combination of a carriage rail or rod; a sleeve 65 slidable and rotatable thereon; a stop longitudinally adjustable on said sleeve and rotatively engaged therewith; a paper car-

riage having an abutment to act against said stop and move it and the sleeve lengthwise the rail or rod; keys; means for locking the same operatively connected with the said sleeve; and a tabulator key adapted to operate 70 said locking means.

53. In a typewriting machine, the combination of a laterally movable paper carriage 75 having an abutment; an end-stop for said abutment to encounter, adapted to move in the same direction as the carriage; keys; means for locking the same by such movement of said stop, said means comprising a lever and a slide rod with one or more abutments to intercept the keys; and a tabulator 80 key adapted to operate said lever.

54. In a typewriting machine, the combination of a laterally movable paper carriage 85 having an abutment; an end-stop for said abutment to encounter, adapted to move in the same direction as the carriage; key levers; a universal bail; a slide rod with one or more abutments to intercept said bail; operative connections between said rod and the end-stop; and a tabulator key adapted to 90 operate said connections.

55. In a typewriting machine, the combination of a laterally movable paper carriage 95 having an abutment; an end-stop for said abutment to encounter, adapted to move in the same direction as the carriage; key levers; a universal bail; a slide rod with one or more abutments to intercept said bail; a lever applied to said rod; a second lever connected with the first and with the said end-stop; and a tabulator key adapted to operate 100 said second lever.

56. In a typewriting machine, the combination of a carriage rail or rod; a sleeve 105 slidable thereon; an end-stop on the sleeve adjustable lengthwise thereof; a paper carriage having an abutment to act against said stop and move it and the sleeve lengthwise the rail or rod; keys; means for locking the same operatively connected with the said 110 sleeve, said means comprising a lever and a slide rod with one or more abutments to intercept the keys; and a tabulator key adapted to operate said lever.

57. In a typewriting machine, the combination of a carriage rail or rod; a sleeve 115 slidable thereon; an end-stop on the sleeve adjustable lengthwise thereof; a paper carriage having an abutment to act against said stop and move it and the sleeve lengthwise the rail or rod; key levers; a universal bail; a slide rod with one or more abutments to intercept said bail; operating connections between said rod and the sleeve; and a tabulator key adapted to operate said connections.

58. In a typewriting machine, the combination of a carriage rail or rod; a sleeve 120 slidable thereon; an end-stop on the sleeve adjustable lengthwise thereof; a paper car-

riage having an abutment to act against said stop and move it and the sleeve lengthwise the rail or rod; key levers; a universal bail; a lever applied to said rod; a second lever connected with the first and with the said sleeve; and a tabulator key adapted to operate said second lever.

59. In a typewriting machine, the combination of a laterally movable paper carriage having an abutment; an end-stop for said abutment to encounter, adapted to move in the same direction as the carriage; keys; means for locking the same by such movement of said stop, said means comprising 10 a lever and a slide rod with one or more abutments to intercept the keys; a tabulator key; a rock shaft operated thereby; and a cam-finger on the rock shaft engaging said lever.
- 20 60. In a typewriting machine, the combination of a laterally movable paper carriage having an abutment; an end-stop for said abutment to encounter, adapted to move in the same direction as the carriage; key levers; a universal bail; a slide rod with one or more abutments to intercept said bail; a lever applied to said rod; a second lever connected with the first and with the said end-stop; a tabulator key; a rock shaft operated thereby; and a cam-finger on the rock shaft engaging said lever.

61. In a typewriting machine, the combination of a carriage rail or rod; a sleeve slideable thereon; an end-stop on the sleeve adjustable lengthwise thereof; a paper carriage having an abutment to act against said stop and move it and the sleeve lengthwise the rail or rod; key levers; a universal bail; a slide rod with one or more abutments 35 to intercept said bail; a lever applied to said rod; a second lever connected with the first and with the said sleeve; a tabulator key; a rock shaft operated thereby; and a cam-finger on the rock shaft engaging said 40 second lever.

62. In a typewriting machine, the combination of a carriage rail or rod; a sleeve slideable and rotatable thereon; a stop longitudinally adjustable on said sleeve and rotatively engaged therewith and having a cam and a stop projection; a paper carriage having an abutment to ride over the cam and act against the stop projection; an arm on the sleeve having a branch carrying a bell striker; a bell; key levers; a slide rod adapted to block movement of the key levers; lever connections between said slide rod and the arm of the sleeve; a tabulator key lever; a rock shaft having an arm under-

lying the same; and a cam-finger on said 60 rock shaft engaging the said lever connections.

63. In a typewriting machine, the combination of a laterally shifttable paper carriage having an abutment; a rod or rail; a 65 stop mounted thereon and longitudinally adjustable and having a projection to be encountered by the carriage abutment, said stop being mounted to rock on the rod for disengaging its projection from said abutment; and a spring on the stop engaging the 70 rod and resisting such rocking movement.

64. In a typewriting machine, the combination of a laterally shifttable paper carriage having a pivoted abutment piece; a 75 rod or rail; a stop mounted thereon and longitudinally adjustable and having a projection to be encountered by the carriage abutment piece, said stop being mounted to rock on the rod for disengaging its projection 80 from said abutment piece; and a spring on the stop engaging the rod and resisting such rocking movement.

65. In a typewriting machine, the combination of a laterally shifttable paper carriage having an abutment; a rail or rod; an 85 end stop piece adjustable thereon in the line of movement of the carriage and also arranged to rock on the rod, said stop piece having a cam ledge and a stop projection 90 spaced therefrom; and a spring on the stop engaging the rod and resisting rocking of said stop piece, the carriage abutment adapted to ride over the cam ledge overcoming said spring and the latter, then 95 restoring the stop piece to present its stop projection to the abutment and the stop piece being capable of rocking movement sufficient to disengage the stop projection from the abutment permitting further travel of 100 the carriage.

66. A typewriting mechanism for typewriting machines including a movable carriage, a stop thereon, a coöperative tabulator stop, an escapement mechanism, releasing means for the escapement mechanism, braking means for controlling the movement of said movable carriage, a universal bar, means for locking said universal bar, means for simultaneously operating said 105 tabulator stop, said releasing means, and said locking means, and applying said braking mechanism.
